UNITED STATES PATENT OFFICE.

THOMAS HANSON, OF NEW YORK, N. Y.

WATER-CLOSET.

SPECIFICATION forming part of Letters Patent No. 255,975, dated April 4, 1882.

Application filed July 7, 1881. (No model.)

To all whom it may concern:

Be it known that I, THOMAS HANSON, of New York, in the county and State of New York, have invented certain new and useful Improvements in Water-Closets, of which the following is a specification.

The object of my improvements is to produce a water-closet in which the basin or bowl will be effectually cleaned and from which the escape of gases will be prevented.

My improvements consist in the combination, in a water-closet, of a basin, a valve-chamber connected thereto, a vertically-arranged valve-seat at the juncture of said basin and chamber, a slide-valve operating in conjunction with said seat to control the escape of the contents of the basin, a guide for said valve, and a guideway parallel with the valve-seat and against which the guide works.

They also consist in the combination, with the basin, valve-chamber, and seat hereinabove described, of a slide-valve having a stem projecting from its back, a resistance-piece having a sliding connection with said valve-stem, and a spring arranged between the valve and its seat.

They also consist in details of construction and combinations of parts, hereinafter described.

In the accompanying drawings, Figure 1 is a sectional side view of a water-closet embodying my improvements. Fig. 2 is a transverse vertical section of the same, taken at the plane of the dotted line $x x$, Fig. 1; and Fig. 3 is a sectional plan thereof.

Similar letters of reference designate corresponding parts in all the figures.

A designates a basin or bowl, which may be made of earthenware or other suitable material, and is shown as of elliptical form, and provided with a side outlet, A', arranged in a vertical plane.

A² designates a pipe whereby the flushing or cleansing water is supplied to the basin. It may be connected with a nozzle formed in one with the basin, or it may be connected with the basin in any other suitable manner. It is shown as arranged for use with an overhead cistern and as communicating with the front of the basin; but it may be connected with any

suitable source or head of water. It is to be provided with a valve of any suitable style, which preferably will be operated by a pull-rod, B, arranged at one side, but near the front of the basin, and operating in the ordinary manner. This pull-rod is connected with an arm, C, on a rock-shaft, D, which is also provided with an arm, E. The arm E is designed to be connected with the valve of the pipe A², the valve being arranged overhead.

F designates a slide-valve arranged in a valve-chamber, G, which is connected with the basin A, and operating with an up-and-down movement in conjunction with the side outlet, A', of the said basin. Preferably there will be combined with the basin A and chamber G a valve-seat, H, of composition, metal, or other material which will not quickly corrode. This valve-seat may be arranged, as shown, so as to form one side of the chamber G, and the valve F will work directly against it.

The valve F has a tubular stem or shank projecting from its back, and is held against its seat by means of a spring, I. This spring acts upon the back of the valve F, and between it and a movable resistance-piece, J, which is provided with a stem that fits in the tubular stem of the valve, F, and hence forms a sliding connection between the resistance-piece and valve, and so connects the resistance-piece and valve that the two will move up and down together. The resistance-piece J also constitutes a guide for the valve, and the adjacent wall of the valve-chamber on which it works constitutes a guideway parallel with the valve-seat. Both the valve and the resistance-piece are guided by the edges of the front and back of the chamber G.

Motion is imparted to the valve F by means of an arm, K, extending from the rock-shaft D and connected with its stem. It will thus be seen that when the pull-rod B is raised the valve F is raised to open the side outlet of the basin A and permit its contents to escape, and that the valve controlling the flow of water through the pipe A² is also operated to admit a quantity of water to the basin. When the pull-rod moves back to its normal position the valve controlling the flow of water through a pipe, A², closes, thereby shutting off the further flow of water, and the valve F also closes

the outlet of the basin tightly and prevents noxious gases from entering the basin through the outlet. The water remaining in the basin seals the valve effectually.

5 At the back of the basin A is an overflow-outlet, A³, which communicates through a pipe or conduit, L, with an overflow-chamber, M. The conduit L and chamber M may be made in one piece with the basin, or they may be 10 made separately and be secured thereto in any suitable manner.

The lower end of the overflow-chamber is controlled by a valve, N, which is connected to one end of a lever, O, which is arranged 15 within the chamber and provided at the other end with a float, P. When the water rises sufficiently in this overflow-chamber the float P is raised and the valve is lowered, so that it will open the aperture in the bottom of the 20 chamber which it controls and permit the water to pass off. Whenever the water-level is lowered sufficiently the float falls, thereby raising the valve N and causing it to close the aperture which it controls. The overflow-chamber 25 is therefore always sealed with water, and noxious gases are precluded from escaping through it into the apartment where the water-closet is located. The water which escapes from the overflow-chamber passes through a pipe or 30 conduit, Q, to the chamber G.

This water-closet may have its outlet connected with any suitable trap, if desirable, and may have a vent-pipe, R, combined with its overflow-chamber M.

35 It will be seen that by my invention I produce a water-closet from which all deposits will be thoroughly discharged, which will be kept clean, and which will prevent noxious gases from escaping into the apartment where 40 it is located.

What I claim as my invention, and desire to secure by Letters Patent, is—

1. In a water-closet, the combination of a basin, a valve-chamber connected thereto, a vertically-arranged valve-seat at the juncture of 45 the basin and chamber, a slide-valve operating in conjunction with said seat to control the escape of the contents of the basin, a guide for said valve, and a guideway parallel with said valve-seat, upon which said guide works, sub- 50 substantially as specified.

2. In a water-closet, the combination of a basin, a valve-chamber connected thereto, a vertically-arranged valve-seat and slide-valve for controlling the escape of the contents of the 55 basin, a resistance-piece having a sliding connection with the stem of said valve, and a spring arranged between said resistance-piece and valve, substantially as specified.

3. In a water-closet, the combination of the 60 basin A, valve-chamber G, slide-valve F, arm K, rock-shaft D, and pull-rod B, substantially as specified.

4. In a water-closet, the combination of the basin A, valve-chamber G, slide-valve F, with 65 its tubular stem, the resistance-piece J, with its stem fitting in the tubular stem of the valve, and the spring I, substantially as specified.

5. In a water-closet, the combination of the basin A, valve-chamber G, slide-valve F, re- 70 sistance-piece J, spring I, overflow-outlet A³, conduit L, overflow-chamber M, valve N, lever O, and float P, all substantially as specified.

THOS. HANSON.
